FUEL CONTROL SYSTEM

Michael J. Thomas, Birmingham, and Guy C. Fricke, Pleasantridge, Mich., assignors to Bendix Aviation Corporation, South Bend, Ind., a corporation of Delaware

Application June 27, 1946, Serial No. 679,774

11 Claims. (Cl. 123—119)

1

This invention relates to fuel supply systems or devices for internal combustion engines and more particularly to devices or systems in which liquid fuel is supplied under positive pressure.

An important object of the invention is to provide a fuel feeding system in which the fuel flow is automatically regulated in accordance with certain engine variables such as, for example engine speed and engine charging pressure.

Another object of the invention is to provide a device of this character that comprises a simple unit which is effective and reliable in operation.

This fuel supply system, while especially applicable to fuel supply systems of the character hereinafter particularly described, is not limited to such uses, but is obviously available, with or without modification, in a great variety of cases where fuel is intended to be supplied under more or less analogous conditions in an internal combustion engine or other fuel consuming device.

Further objects and advantages of the invention will be apparent, to those skilled in the art, from the following detailed description, taken in connection with the accompanying drawings. From the disclosed embodiments, skilled persons will understand that many variations may be made without departing from the principles disclosed, and we contemplate the employment of any structures, arrangements, or modes of operation that are properly within the scope of the appended claims.

In the drawings:

Figure 1 is a schematic view of a fuel system embodying the present invention;

Figure 2 is a section taken on line 2—2 of Figure 1;

Figure 3 is a side view of the fixed orifice plate;

Figure 4 is an edge view of the rotatable distributor plate;

Figure 5 is a side view of same taken on line 5—5 of Figure 4; and

Figure 6 is a partial schematic view of a fuel system embodying the present invention and including a variant thereof.

Throughout the drawings similar reference numerals indicate similar parts except where such parts vary in structure and function, in which case they are given a further differing reference character.

Referring first to Figure 1, there is shown a fuel pump indicated generally at 10 in a housing 12 to one end of which is secured an extension 14. The pump, Figures 1 and 2, includes a pump stator 16 having an interior chamber 18 in which

2

a rotor 20 is operatively disposed. The rotor is attached to a shaft 22 by a key 24, said shaft preferably being driven by the engine although it may be otherwise operated. Vanes 26 and 27 are slidably received in recesses 28 and 29 provided therefor and the inner ends of said vanes are adapted to engage the periphery of the rotor, the rotor being mounted on shaft 22 and having three equally spaced longitudinal portions for operatively engaging the peripheral wall of said chamber 18. The vanes are urged against the surface of the rotor by springs 30 and 31. Fuel enters the pump through the inlet 32 which communicates with the interior of chamber 18 by way of passages 34 and 35, and fuel is discharged from chamber 18 by way of passages 36 and 37. The passages 34 and 35 are located adjacent one side of the vanes 26 and 27 and the inlets 38 and 39 of passages 36 and 37 are located adjacent the other side of said vanes. As shown, the passages 36 and 37 communicate with a passage 40 which communicates with a chamber 42 through a port 43 controlled by a valve 44. The upper wall of chamber 42 is closed by a flexible diaphragm 46 which has spring retainers 48 and 50 secured thereto, adjacent the central portion thereof, by a rivet 52. A spring 54 reacts between the spring retainers 48 and a flange 56 of the valve 44 and a spring 58 reacts between the spring retainers 50 and a flanged spring retainer 60 of a plunger 62 which is slidably received in an extension 64 of a housing 66. The housing 66, together with the diaphragm 46, defines a chamber 68. Chamber 42 is connected with the passage 34 by a passage 72 comprising a by-pass from the discharge side having orifice 73 therein to the intake side of the pump.

Fuel discharged by the pump and conveyed by passages 36 and 37 passes through passage 40 into a chamber 76 in a housing 12 through which shaft 22 extends. Within the chamber 76 is a sleeve 78 which is keyed at 80 to said shaft to prevent rotation between the sleeve and shaft, but said sleeve has a limited amount of longitudinal movement on the shaft which is permitted by a groove 82 in which said key is disposed. The sleeve is provided with an annular flange 84 against which one end of a spring 86 reacts to urge said sleeve to the left, as shown in Figure 1. The opposite end of the spring 86 reacts against a spring retainer 88 which is limited in its movement to the right, as shown in Figure 1, by a spring clip 90 received in an annular groove provided therefor in the shaft 22. A fixed orifice plate 92, Figures 1 and 3, is secured to the exten-

sion 14 by any suitable means such as screws 94 received in countersunk holes 96 in said plate 92. Rotatable on shaft 22, between the plate 92 and the sleeve 78 is a baffle plate 98 which has a serrated or toothed peripheral edge 100. Figures 4 and 5, and a flange portion 102 which has a toothed end portion 104. The teeth 104 are adapted to be engaged by corresponding teeth in the adjacent face of the flange 84 of sleeve 78. This arrangement permits rotatable adjustment of the plate 98 relative to the sleeve 78 for varying the timing of the passage of fuel through orifices 106 in the plate 98 which are in substantially the same circumferential plane as orifices 108 in the fixed plate 92. However this arrangement prevents accidental rotation of plate 98 on the shaft. Adjustment of the plate 98 relative to sleeve 78 may be effected by any suitable instrument which may be inserted in an opening into chamber 76, said opening being normally closed by a threaded plug 110. The orifices 108 are in constant communication with fuel discharge passages 112 which communicate with conduits 114 leading to fuel discharge nozzles, indicated generally at 116.

The nozzles 116 include a fitting 118 and a lateral, externally threaded extension 120 which is screwed into an opening in a boss 122 of intake manifold 124 of the engine, not shown. The fitting 118 has a longitudinal extending fuel passage 126 and a branch passage 128 which is controlled by a ball valve 130 urged in the closing direction by a spring 132 which reacts between said ball and a diffusing cup 134 which has discharge passages 136 therein. A gasket 138 is provided between the fitting 118 and the boss 122 to seal same against leakage between the parts. If one discharge nozzle is adapted to supply fuel to more than one cylinder the nozzle may be provided with a plurality of fuel conduits for supplying the required amount of fuel for the additional cylinders. In the drawings, supply nozzle 116 is provided with conduits 114 and 139, the latter conduit being connected to the source of fuel through another conduit 114, discharge passage 112 and orifice 108. As shown in Figure 1, one conduit 114 leads to one side of the manifold and the other conduit 114 may lead to the opposite side of the manifold for connection for fuel nozzles disposed therein. Preferably, though not necessarily, the nozzles discharge adjacent mixture outlets 140 of the manifold to thereby effect improved mixture distribution to the engine in which the manifold 124 has an inlet section 142 which is controlled by throttle valve 144 mounted on a shaft 146 to which a throttle lever 148 is attached. The free end of lever 148 is connected by a rod 150 with the conventional accelerator pedal mechanism, not shown.

Control of the effective pump discharge pressure is regulated in accordance with manifold vacuum or engine charging pressure and engine speed. The manifold vacuum is transmitted from the manifold 124, posterior to the throttle valve 144, by a conduit 152 which communicates with the chamber 68 thereby subjecting the diaphragm 46 to said manifold vacuum on said engine charging pressure to thereby vary the effective closing force of the valve 44.

The speed responsive device for controlling the effective closing force of valve 44 in cooperation with the manifold vacuum comprises a fly ball governor having a yoke comprising arms 160 in the central collar 162 secured to the shaft 22 by a pin 164. To each arm 160 is attached a lever 165 pivoted at 166 to said arms and having weight-

ed free ends 168, said levers 165 being adapted to move outwardly in response to centrifugal force when the shaft 22 is rotated; each lever is provided with a laterally extending arm 170 which is adapted to engage the adjacent face of a flange 172 formed on a sleeve 174 slidable on the shaft 22, said sleeve being adapted to be moved to the left, as shown in Figure 1, by the arms 165. The opposite end of sleeve 174 is adapted to engage a bifurcated arm 176 secured to a collar 178 which is fixed to a shaft 180 by a set screw 182. The shaft 180 is journalled in the walls of a housing 184 which encloses the governor mechanism and is attached to the extension 14 by any suitable means such as screws, not shown. Also attached to the shaft 180 is a lever 185 connected to an arm 186 of a bell crank by means of a rod 188. The bell crank is pivoted at 190 and has an arm or cam 192 adapted to engage the plunger 62 to effect longitudinal movement thereof. The cam surface of the bell crank may be contoured to provide an economical fuel-to-air ratio for normal engine operation and an enriched mixture when the engine is under heavy load. A spring 194 has a connection with lever 185 and another connection with a fixed arm 196 and urges the lever 185 in a counterclockwise direction, as shown in Figure 1. When the shaft 22 is rotated to cause the arms 164 to move outwardly the lever 185 is moved in a clockwise direction, as shown in Figure 1, thereby effecting inward movement of the plunger 62.

It is to be noted that suitable bearings are provided for the shaft 22, there being a bearing 198 in the housing 12, bearing 200 in the extension 14 and a bearing 202 in the closed end of the housing 184. In order to prevent the escape of fuel past the shaft 22, seals 204 and 206 are provided in the housing 12 and extension 14 respectively.

Operation

During operation of the device the rotor 20 pumps fuel into the passages 36 and 37 through the passage 40 and into the chamber 76. A portion of said fuel however is by-passed through port 43, past valve 44 into passage 72 and thence to the inlet side of the pump, and the effective force of spring 58 and the manifold pressure in chamber 68 urging valve 44 in the closing direction determines the amount of fuel by-passed and consequently determines the discharge pressure of the fuel conveyed to the chamber 76. As the shaft rotates, the orifices 106 in the plate 98 intermittently communicate or register with the orifices 108 in a fixed plate 92. During the periods said orifices 106 and 108 are in register, fuel passes therethrough and into the conduits 112, thence through the conduits 114 to the fuel nozzles 116. Such fuel is then discharged into the intake manifold 124 by way of the orifices 136 in the diffuser cup 134. It is to be noted that for every revolution of the shaft 22 the orifices 106 and 108 are in register or communication for passing fuel throughout a fixed portion of each revolution regardless of the speed of rotation of said shaft 22. Thus a fixed quantity of fuel will flow through said orifices for a given pump pressure.

By varying the effective pressure of springs 54 and 58 urging the valve 44 in the closing direction variations in the effective pump discharge pressure are secured. With high suction in the manifold 124, the diaphragm will be urged outwardly, relative to the valve 44, to effect lessening of the effective forces tending to close valve 44.

Conversely a drop in manifold suction will permit said springs to exert a greater effective closing force on said valve. Thus with the throttle in a substantially closed or idling position, at which time the manifold vacuum is high, the valve 44 will permit a relatively large quantity of fuel to be by-passed, and thus the fuel pressure in chamber 76 will be relatively low for providing the proper quantity of fuel for the desired fuel mixture. Should the throttle valve 144 be opened, as for acceleration of the engine, the vacuum in chamber 68 will drop, in other words, the pressure in said chamber will rise, permitting the springs 54 and 58 to exert a greater effective closing force on the valve 44, thereby effecting a rise in the pressure of fuel in chamber 76 and effecting a greater quantity of fuel to be discharged from the nozzles 116, thus providing an increase in fuel flow corresponding to an increase in air flow accompanying an acceleration.

At the same time, as the shaft 22 is rotated, the free ends of the levers 164 will move outwardly under the influence of centrifugal force and effect clockwise movement of the lever 185 which in turn will effect an inward movement of the plunger 62. At relatively low speeds the influence of the governor will be relatively slight. As the speed of the engine increases the arms 164 move outwardly and effect inward movement of the plunger 62 thereby increasing the effective valve closing force of springs 54 and 58 thereby increasing the fuel pressure in chamber 76 and providing for an increase in fuel flow as required by the increase in air flow accompanying the increased engine speed.

Figure 6

In the arrangement shown in Figure 6 a governor throttle 210 is provided in the air inlet passage 142; the valve 210 is mounted on a shaft 212 which has a lever 214 secured thereto adjacent one end. The free end of lever 214 is connected by a rod 216 to the free end of the lever 185.

With this arrangement the top speed of the engine may be limited by action of the governor mechanism which, as the speed of the engine increases, effects a corresponding closing movement of the governor throttle 210.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the arrangements hereinabove described being merely preferred embodiments.

We claim:

1. In a fuel supply system for an internal combustion engine having an intake manifold: a fuel pump for receiving fuel from a source and for delivering the fuel to said manifold; a passage from the outlet side of the pump for said fuel; a fuel nozzle connected with said passage; a by-pass from the outlet side to the inlet side of the pump; a valve for controlling the flow of fuel through said by-pass, a yieldable means for urging the valve toward the closed position; and means operative throughout the engine operating range for varying the effective force tending to close said valve in accordance with engine speed and charging pressure.

2. In a fuel system for an internal combustion engine having an intake manifold: a fuel pump

receiving fuel from a suitable source; a passage from the outlet side of the pump; a fuel nozzle connected with said passage; a by-pass from the outlet side to the inlet side of the pump; a valve controlling said by-pass; yielding means urging the valve in the closing direction; means for varying the effective force of said yielding means in accordance with engine charging pressure; and means responsive to engine speed for increasing the valve closing force of said yielding means on increase in engine speed, said pressure and speed responsive means being operative throughout substantially the full engine operating range.

3. The invention defined by claim 2 wherein there is a fixed orifice and a rotatable plate having openings therein adapted to register with the fixed orifice upon rotation of said plate.

4. In a fuel system for an internal combustion engine: a sliding vane type of pump having an inlet and an outlet; said pump receiving fuel from a suitable source; a by-pass from the outlet to the inlet side of the pump; a valve controlling said by-pass; yielding means urging the valve in the closing direction; a shaft for driving said pump and adapted to be operatively connected with the engine; a fuel passage from the outlet side of the pump and having a plurality of connections with the engine; a fixed orifice for each of said connections, said orifices being circumferentially arranged about the shaft in radially spaced relationship; a rotatable disc mounted on the shaft and having at least one opening therein adapted to intermittently register with said orifices upon rotation of the shaft; a device connected with the shaft and responsive to the speed thereof; means connecting said device with the yielding means for varying the effective force thereof; and means responsive to engine charging pressure for modifying the effect of the device on said yielding means.

5. The invention defined by claim 4 wherein the disc is rotatably adjustable on the shaft.

6. The invention defined by claim 4 wherein there is a clutch interposed between the shaft and the disc whereby the rotational position of the plate on the shaft is adjustable.

7. The invention defined by claim 4 wherein the device comprises a flyball governor.

8. The invention defined by claim 4 wherein the engine includes an intake manifold having an inlet; a valve controlling said inlet; and means connecting said valve with said device whereby the quantity of fluid entering the manifold is controlled in accordance with engine speed.

9. In a fuel system for an internal combustion engine: a variable output fuel pump; a fuel conduit connecting the pump with the engine; a device responsive to engine speed for varying the output of the pump; and means responsive to engine charging pressure for modifying the effect of the speed responsive device in varying the pump output, said speed responsive device and pressure responsive means being operative throughout the engine operating range.

10. In a fluid metering device: a shaft; a fixed member on the shaft, said shaft being rotatable therein; a plurality of metering orifices in the member disposed annularly about the shaft in spaced relation with each other; a plate mounted on the shaft and adapted to move longitudinally thereon, said plate having at least one orifice in substantially the same annular plane as the first mentioned orifices; peripheral teeth on the plate; a plurality of teeth on one face of the plate; a sleeve on the shaft held against rotation there-

on but having limited longitudinal movement; teeth adjacent one end of the sleeve adapted to engage the teeth on the side of the plate; and yielding means urging the sleeve toward the plate.

11. In a fuel system for an internal combustion engine: a variable output fuel pump having an inlet and an outlet; means for connecting the pump with the engine for operation thereby; a device responsive to engine speed operative throughout the engine operating range for varying the output of the pump; a device responsive to manifold vacuum for varying the output of the pump; a fuel conduit leading from the pump to the engine intake manifold; a fuel nozzle with which the conduit is connected and a spring ¹⁰ ₁₅ pressed valve closing the nozzle fuel passage.
